UNITED STATES PATENT OFFICE

ALEXANDER L. GEITNER, OF ROCHESTER, NEW YORK

COUNTERBORE

Application filed March 16, 1929. Serial No. 347,573.

This invention relates to counterboring tools and has for its various objects:

To provide a counterbore which is both simple and strong in construction and in which the individual cutters may be individually and collectively adjusted to compensate for wear.

To provide locking means for each of the cutters with which a step by step adjustment of the cutters in the body of the counterbore may be secured.

To provide a counterbore in which the separate cutters are provided with a cutting edge at right angles to the axis of rotation the full width of the cutter and with a cutting edge parallel to the axis of rotation adjacent to the right angle cutting edge along a fraction of the length of the cutter.

To provide a guide slot for each of the cutters of the counterbore in which the cutter may be adjusted radially as well as laterally to compensate for any wear in both of the cutting edges.

All these and other objects of this invention will be apparent from the accompanying drawing, the specification and the appended claims forming a part thereof.

In the accompanying drawing:

Figure 1 is a side elevation of the complete counterbore partially broken away.

Figure 2 is an end elevation of the counterbore.

Figure 3 is a detail sectional view of a portion of the counterbore illustrating one of the locking means for clamping a cutter in place in the head of the counterbore, the section being taken on the line 3^x—3^x of Figure 1.

Figure 4 is a sectional view of the head of the counterbore illustrating a modified form of holding the cutters in place therein.

Figure 5 is a side elevation of a portion of the head of the counterbore illustrating another modified form of locking the individual cutters in place therein.

Figure 6 is a partial longitudinal sectional view of another modified form of the head of the counterbore.

Figure 7 is a vertical cross section of the counterbore illustrated in Figure 6, the sec-

tion being taken on the line 7^x—7^x of Figure 6.

Figure 8 is a side elevation of the cutter.

The counterbore forming the subject matter of my present invention is an improvement over other counterboring tools on which I have secured Letters Patent. The present improvements consist mainly in the manner in which the individual tools are provided with cutting edges and the manner in which these cutters are held against endwise movement in the head of the counterbore.

In the several figures of the drawing like reference numerals indicate like parts.

As illustrated in Figure 1 the counterbore comprises the head 1 which is provided with a shank 2 at the rear and with the pilot 3 at the front thereof. The shank 2 is integral with the head of the counterbore and while I have shown it tapered, a straight shank 70 may be provided instead. The pilot 3 is removable from the head and for this purpose the center of the head 1 is drilled out to provide a longitudinal hole therein which is adapted to receive the shank 4 of the pilot. 75 As illustrated in Figure 1 the head 1 is drilled the full length of it and from the rear of the hole extends the duct 5 which leads angularly to the outside of the shank 2 of the counterbore. The hole in the head is thus open 80 at both ends and this precludes any possibility of filling the hole in the head, as any substance lodged in the hole may be blown out or forced out thru the duct 5 or forced out of the hole by blowing thru the duct into the 85 hole or forcing a suitable instrument thru the duct into the hole.

In the head 1 of the counterbore are provided the guide channels 6, 6 of which four are shown in number, although larger or smaller numbers of guide slots may be provided instead. In each of the guide channels is mounted a cutter 7. The guide slots extend in the body in an angular direction both in the vertical and the horizontal plane 90 so that a movement of the cutter out of its guide channel will not only move the vertical or radial cutting edge forwardly of the head but will also move the short longitudinal cutting edge outwardly of the head. In 100

this way any wear in both of the cutting edges due to the regrinding of these cutting edges may be simultaneously compensated for by a movement of the cutters out of the 5 guide slots in the head of the counterbore.

5 In the form of the counterbore illustrated in Figure 1 the adjustment of the cutters in the head is secured by the ring nut 8 which, for this purpose, is threaded to the threaded 10 rear portion of the head as illustrated in Figure 1. The rear end of all of the cutters 7 rest against the front face of the ring nut so that on threading the nut forwardly on the head all of the cutters are simultaneously forced forwardly in the head with the result above described.

For the purpose of clamping the cutters in place in their respective guide channels each cutter is provided with a longitudinal 20 groove 9 into which is adapted to extend an eccentric washer 10. This washer is located in a suitable cylindrical pocket alongside of the guide channel and thru it passes the shank of the clamping screw 11. The clamping screw is threaded into the head below the cylindrical pocket so that in screwing the clamping screw down onto the eccentric washer the head of the screw forces the eccentric washer down into the pocket. The overhanging 25 portion of the eccentric washer which projects into the groove in the side of the cutter at the same time forces the cutter in place in its guide channel whenever the clamping screw is tightened against the washer. The bottom of the groove in the cutters is beveled and the overhanging portion of the eccentric washer 9 which extends into the groove is correspondingly beveled so that on the downward movement of the washer the 30 cutter is not only forced downwardly against the bottom of the guide channel but also outwardly against the side of the guide channel. The cutters 7, 7 are thus adjustably clamped in place and held against radial 35 movement in the head by means of the clamping screws 11. The ring nut 8 on the other hand serves to hold the cutters against longitudinal movement in the head against the pressure exerted when the cutters are forced 40 against the work.

Counterbores have heretofore been used to face off the immediate area surrounding an opening. The present tool is used for this same purpose but in addition is adapted to 55 be used for the purpose of facing off a cylindrical surface surrounding the area around an opening. In this way the wall, as well as the end of a cylindrical pocket forming an extension of a hole, may be finished off by means 60 of the counterbore illustrated and described. The radial cutting edges formed at the outer ends of the cutters the full width thereof finish off the end of the pocket or the immediate area surrounding the hole, while the longitudinal cutting edge, which is parallel to 65

the axis of rotation of the counterbore and extends a short distance rearwardly from the radial cutting edge, finishes off the wall of the pocket.

In Figures 4 and 5 I have illustrated two modified methods of holding the cutters 70 against endwise movement in their guide channels. In the method illustrated in Figure 4 the bottom of each cutter is provided with a series of notches, 20, 20 which are suitably spaced either at regular or irregular intervals. The periphery of a washer 21 surrounding the shank of the pilot and suitably spaced from the rear of the pilot extends into one of these notches so that when the cutter is forced down into its guide channel by the clamping screw, one of the notches is also forced in place over the washer which then forms a shoulder which serves to hold the cutter against endwise movement in the 75 guide channel. The washer is located between the pilot and the end of the head and is thus held fixed against movement on the shank of the pilot. As the front cutting edge of the cutter is ground back until the first of the notches no longer can be engaged by the washer to hold the cutter against movement, the cutter is moved forward in the guide channel until the next notch engages the washer. In this way a step by step longitudinal adjustment may be secured for the cutter without the use of the ring nut illustrated in 80 Figure 1.

In the modification illustrated in Figure 5 the same step by step longitudinal adjustment is secured by providing one side of each cutter with a series of grooves 30, 30 beginning at the rear end thereof. A corresponding groove is provided in the opposite side of the guide channel into which the cutter is inserted so that the groove in the channel and one of the grooves in the cutter provide an opening into which the key pin 31 may be inserted. The engagement of the key pin in both the groove in the side of the channel and the side of the cutter then holds the cutter against movement in the guide channel thus dispensing with the ring nut 8 for this purpose. When the cutter must be moved forwardly in the guide channel the key pin 105 is withdrawn to allow the cutter to be moved longitudinally in the guide channel until the next groove in the side of the cutter is located opposite the groove in the channel and allows the key pin to be inserted between them.

The modification illustrated in Figures 6 and 7 combines the adjustment provided by the ring nut 8 and the adjustment provided by the washer 20. As illustrated in these 110 figures two cutters 40 and 41 are held in place in the head of the counterbore. The bottom or inner cutter is notched as described in connection with Figure 4 and is engaged by the washer 20 for the purpose of holding 115

it against endwise movement in the guide channel. The upper or outer cutter is backed against the ring nut 8 in the manner described in connection with Figure 1 and is held against endwise movement by this ring nut. Both cutters are clamped in place in the guide slot by a suitable clamping means such as are illustrated in Figure 7 in which the upper cutter is forced down upon the lower cutter by means of the clamping screw 42 and the eccentric washer 43.

In this form of counterbore the cutting edge of the inner cutters is used to face off the immediate area surrounding the hole, 15 while the cutting edge of the outer cutters finishes off in a predetermined form, depending on the outline of the cutting edge, the area adjacent to the area surrounding the hole. The adjustment secured by the ring 20 nut also makes it possible to adjust the outer cutters independently of the inner cutters.

I claim:

1. A counterbore having a head with a shank at the rear of the head and a pilot at 25 the front of the head, said head having a plurality of laterally angular guide channels cut therein inclined upwardly from the rear end of the head to the front end thereof, a cutter of uniform width and thickness mounted 30 in each of said inclined guide channels, a cutting edge provided at the forward end of each of said cutters and disposed radially to the front end of said head, and a short cutting edge provided along the outer edge of 35 each of said cutters extending rearwardly of said front cutting edge and at right angles thereto and at an angle to the top and bottom of the cutter.

2. A counterbore having a head with a shank at the rear end and a pilot at the front 40 end of the head, said head having a plurality of cutters angularly mounted therein at an incline extending outwardly from the rear of the head, each of said cutters being of uniform width with one cutting edge formed at 45 the forward end thereof, a second cutting edge formed along the top of each of said cutters at right angles to the forward cutting edge and at an angle to the top and bottom 50 of the cutter and extending rearwardly from said forward cutting edge, each of said cutters having a longitudinal groove in the side 55 of said cutters extending forwardly from the rear end and parallel to the bottom thereof, said groove having a downwardly inclined bottom, a washer extending into said groove, an inclined ledge on the under side of said washer and engaging said inclined bottom of 60 said groove and means for forcing said washer downwardly to force said cutter downwardly and outwardly in said head.

3. A counterbore having a head with a shank at the rear and a pilot at the front, a plurality of guide channels in said head, 65 a cutter located in each of said guide chan-

nels, a shoulder carried by said head behind its pilot, a series of notches in the bottom of said cutters adapted to individually engage over said shoulder and means for clamping said cutters in place in said guide channels 70 with said shoulder engaging into one of said notches in each of said cutters to hold said cutters against radial movement in said head.

4. A counterbore having a head with a shank at the rear and a pilot at the front, a plurality of guide channels in said head, cutters located in said guide channels, means provided at the bottom of said cutters and cooperating with said pilot to hold said cutters against endwise movement, means provided in said head and means provided in the side of said cutters and cooperating with the means in said head to hold said cutters 75 against outward movement.

5. A counterbore having a head with a shank at the rear and a pilot at the front, a plurality of guide channels in said head, a pair of cutters in each of said guide channels one on top of the other, means provided in the bottom of the inner cutters to hold said 80 inner cutters against endwise movement in said guide channels and means carried by said head and engaging the rear of said outer cutters to hold said outer cutters against endwise movement in said guide channels. 85

6. A counterbore having a head with a shank at the rear and a pilot at the front, a plurality of guide channels in said head, a pair of cutters in each of said guide channels one on top of the other, means provided in the bottom of the inner cutters to hold said 90 inner cutters against endwise movement in said guide channels and means carried by said head and engaging the rear of said outer cutters to hold said outer cutters against endwise movement in said guide channels. 95

7. A counterbore having a head with a shank at the rear thereof, and an axial hole extending into the front end thereof, a pilot, a shank at the rear of said pilot adapted to engage into the axial hole in said head, means for clamping said shank of said pilot in place in said head, a washer carried by said pilot shank and spaced from the rear of said pilot and held against the front of said head, a plurality of cutters carried by said head, a notch in the bottom of each of said cutters adapted to engage over the periphery of said washer to hold said cutters against endwise movement in said head and means for clamping said cutters in place in said head with 100 said notch in engagement over said washer. 110

In testimony whereof I affix my signature.
ALEXANDER L. GEITNER.
